PROCESS AND APPARATUS FOR CUTTING
GARMENT LABELS AND THE LIKE

William A. Burkey, Reading, Pa.

Application December 22, 1937, Serial No. 181,159

8 Claims. (Cl. 270—61)

My invention relates to a simplified and improved process and apparatus for forming garment labels and the like from a usual tape or strip of material commonly bearing a printed or woven series of labels arranged end-to-end and intended for individual use by cutting them apart and in-folding their ends to avoid unsightly raw edges liable to ravel.

Among the main objects of my present improvements are, to provide for severing, without change or adjustments, varying label lengths from tape or strip material of varying widths; for increasing production capacity by providing for continuous folding, creasing, and cutting operations, limited only by the skill of the operator in cross-wise feeding the label-parting portions of the tape or strip material; adjustment for variation of thickness in the label-bearing material; and provision for changing the length of the in-folded label ends.

The apparatus for carrying out my improved process is closely related thereto, and comprises folding, creasing and cutting means arranged for a continuous sequence of operations on each cross-wise-fed parting-portion of the tape or strip of label-bearing material, with provision for adjustment according to the thickness of different label-bearing material, and for varying the length in-folded at the cut-off end of each label.

More specifically, the apparatus consists of a compact machine in which one part of the folding means, in the form of a grooved block or spaced blade edges, is supported on a fixed base, with its cooperating folding means, in the form of a single blade edge depending between said spaced edges, is adjustably suspended from above with a projecting end extended between bend-creasing means, in the form of adjustably-spaced driven rollers, the projecting blade-end beyond said creasing rollers being forked to receive the strip-cutting means, in the form of a rotated disc; the machine having proper bearings and driving means for said rollers and disc.

My improved process and the apparatus for carrying out the same and its manner of operating, will be more fully described hereinafter in connection with the accompanying drawing, and the novel features thereof particularly set forth in the appended claims.

Referring to the drawing which shows a preferred embodiment of my invention,—

Fig. 1 is a perspective elevation.

Fig. 2 is a partial longitudinal sectional view.

Fig. 3 is a corresponding sectional plan view,

but showing a modified adjustable mounting for the spaced folding-blade members.

Fig. 4 is a modified cross-sectional elevation showing provision for varying the spacing of the bend-pressing creasing rollers.

Fig. 5 indicates the label strip with a cut-off end label.

In the drawing 1 indicates the base or bed-plate of the machine formed with an overhanging arm 2 and a central opening 3, with bearings 4, 4, at the side edges of the latter for a transverse shaft 5 carrying a pulley 6 for a driving belt 7 extending through said opening 3 to a suitable driving pulley, not shown. The bed-plate, as shown in Figs. 1 and 2, is formed with ribs 8, 8, spaced to fixedly carry a guide-block 9 divided by a central longitudinal groove 10, into two spaced folding blade members 11, 11. Fig. 3 shows an alternative way of forming these blade members as two angular strips, 11a, 11a, the flanges 12, 12 of which are slotted for screw bolts 13, 13 engaging the base 1 and providing for adjustably spacing said blades.

A cooperating folding blade 15, suspended between the blade members 11, 11, is shown as mounted in the downwardly directed end 17 of arm 2, and secured therein in vertically adjustable positions by means of bolts or screws 18, 18, engaging through blade slots 19, 19.

The arm 2 is shown with a rear bearing 20, 30 and opposed pairs of bearings 21, 21 and 22, 22 on opposite sides of the end 17. A shaft 23, extending upwardly through base 1 from a driven source, not shown, is mounted in bearing 20 and provided with a pulley 23' for a belt 24 extending to a pulley 25 on a shaft 26 mounted in bearings 21 and 22 on one side of arm-end 17. A like shaft 27 is mounted in the opposite side bearings 21, 22, and meshing top gears 28 and 29 on the respective shafts 26 and 27 provide for their joint rotation. Knurled rollers 30 and 31 on the lower ends of the respective shafts 26 and 27 form bend-creasing rollers arranged in cooperative relation on opposite sides of the rearwardly projecting end of plate 15. These creasing rollers may have a fixed spread as shown in Figs. 1 to 3, but in Fig. 4 I have shown one means for adjusting their spread, in which the shafts 26a and 27a are flexible, and the bearings 22a and 22a are slidably mounted in extensions 22b, 22b on the depending arm end 17a, lock-nut screws 32, 32 forming means for varying and locking the bearings 22a and 22a in adjusted spaced relation.

The rearwardly projecting end of plate 15 is

shown as recessed or bifurcated at 35 to receive a cutting device in the form of a cutter disc 36 mounted on driven shaft 5, such bifurcated end positioning the cutter disc close to the creasing rollers 30 and 31 and covering the fabric strip except at the line of cutting along the base bend of the loop formed therein.

From the foregoing description it will be seen that the folding means, blades 11, 11 and 15, 10 creasing means, rollers 30 and 31 co-operating with blade 15, and cutting means, disc 36 projecting into the bifurcated end 35 of blade 15, are arranged in an alignment for a continuous sequence of operations on the tape or strip which 15 is fed crosswise thereto. The strip of label-bearing material is laid across the blades 11, 11, with the line of severance between the labels, positioned between said blades, and then said strip is fed crosswise, with blade 15 cooperating 20 with blades 11, 11 to form a loop in the strip, as clearly seen in Figs. 1, 2 and 3, the advancing edge of said strip coming into the pressing action of rollers 30 and 31 which act against the blade 15 to crease the base bends 41, 41 of said 25 loop, and further advance of the strip brings the intermediate bend 43 of said loop into contact with the cutting disc 36. The preferred practice is to sever the labels in succession beginning at an end of the strip and progressing 30 toward the other end, and at each label severing it will be seen an infold 45, 45, Fig. 5, is formed on the new end of the strip and on the severed end of the cutoff label 46, such in-folds 45, 45 having their bends set by action of the creasing 35 rollers 30 and 31.

My process of continuous operations in sequence on the cross-wise-fold label strip greatly increase production, as its actions are not limited by a cycle of operations, or required operative starting for each cutting, but may be at any rate of speed the skill of the operator develops in cross-wise-feeding the parting-portions of the strip of label bearing material. The apparatus described carries out my continuous sequence of operations; is ready to act without change or adjustment on labels of varying length and varying width; the adjustment of blade 15 provides for varying the label-end in-fold as desired; and the adjustment of the speed of rollers 30 and 31, provided for a regulated pressure of their bend-creasing action and for adjustment according to the thickness of the label-bearing material; and the several labels are severed at a definitely located line of parting with equally infolded creased ends ready for their use as garment labels or the like.

It is believed that the nature of my invention and the means for carrying it out will be clearly understood from the foregoing description, and it is intended to include changes and modifications of the particular embodiment disclosed that properly come within the spirit of my invention as particularly defined in the following claims.

What I claim is:

1. In a machine for severing from a strip of label-bearing material successive end labels having in-folded ends, means for sequentially acting on each cross-fed label-connecting portion, comprising cooperating means for forming a loop-fold across said strip, roller pressure means for creasing the base-bends of said loop fold, and rotary means for severing said strip at the intermediate-bend of said loop fold.

2. In a machine for severing from a strip of label-bearing material successive end labels having in-folded ends, continuously operating means sequentially acting on each cross-fed label-connecting portion, comprising spaced folding-blades and a co-operating folding blade for forming a loop-fold across said strip, rotated pressure-rollers for creasing the base-bends of said loop folds and a rotated cutter-disc for severing said strip at the intermediate-bend of said loop fold. 5

3. In a machine for severing from a strip of label-bearing material successive end labels having in-folded ends, continuously operating means sequentially acting on each cross-fed label-connecting portion, comprising spaced folding-blades 15 and a co-operating folding blade for forming a loop-fold across said strip, rotated rollers having adjustable pressure-regulating means for creasing the base-bends of said loop-fold and a rotated cutter-disc for severing said strip at the 20 intermediate-bend of said loop-fold.

4. In a machine for severing from a strip of label-bearing material successive end labels having in-folded ends, continuously operating means sequentially acting on each cross-fed label-connecting portion, comprising spaced folding-blades and an adjustable cooperating folding blade for forming a loop fold of a determined length across said strip, rotated rollers having adjustable pressure-regulating means for creasing the base 30 bends of said loop-fold, and a rotated cutter disc for severing said strip at the intermediate-bend of said loop-fold. 25

5. A machine for severing from a strip of label-bearing material successive end labels having in-folded ends, comprising a bed plate having an over-hanging arm, spaced loop-folding blades and a rotatably driven cutter disc mounted on said bed plate in longitudinally spaced alignment, a co-operating loop-folding blade mounted on said over-hanging arm to depend between said spaced loop-folding blades and having its rearwardly extended end bifurcated to extend on opposite sides of said cutter disc, and cooperatively driven shafts mounted on said over-hanging arm and having pressing rollers spaced on opposite sides of said arm-held loop-folding blade intermediate the base-supported spaced loop-folding blades and the rotated cutter disc. 35 40 45

6. In the mechanism set forth in claim 5, means for adjustably positioning the arm-carried loop-folding blade relative to the bed-supported spaced loop-folding blades. 50

7. In the mechanism set forth in claim 5, means for adjustably regulating the spread of the pressure rollers relative to arm-carried loop-folding cutter blade intermediately positioned between them. 55

8. The improved method of severing labels with infolded ends from a continuous strip of label material, which consists in successively cross-feeding said strips at each label-connecting portion, and during each of said cross-feedings sequentially forming a loop fold across said strip, creasing the bends of said loop with a rolling pressure, and cutting said strip crosswise 60 65 between said bends, whereby a label is severed from said strip having an infolded creased end, and a creased infold is formed on the free end of said label strip.

WILLIAM A. BURKEY. 70

CERTIFICATE OF CORRECTION.

Patent No. 2,146,934.

February 14, 1939.

WILLIAM A. BURKEY.

It is hereby certified that the residence of the patentee in the above numbered patent was erroneously described and specified as "Reading, Pennsylvania" whereas said residence should have been described and specified as Hamburg, Pennsylvania, as shown by the records of this office; and that the said Letters Patent should be read with this correction therein that the same may conform to the record of the case in the Patent Office.

Signed and sealed this 28th day of March, A. D. 1939.
